(57) **CLAIM**

The ornamental design for a receptacle module for a tabletop media center, as shown and described.

DESCRIPTION

FIG. 1 shows a top perspective view of a receptacle module for a tabletop media center according to a first embodiment. FIG. 2 shows a top view of the receptacle module for a tabletop media center according to the first embodiment. FIG. 3 shows a front view of the receptacle module for a tabletop media center according to the first embodiment. FIG. 4 shows a rear view of the receptacle module for a tabletop media center according to the first embodiment. FIG. 5 shows a left side view of the receptacle module for a tabletop media center according to the first embodiment. FIG. 6 shows a right side view of the receptacle module for a tabletop media center according to the first embodiment. FIG. 7 shows a top perspective view of the receptacle module for a tabletop media center according to the first embodiment, wherein the tabletop media center shown in broken lines illustrates the environment in which the design is used and forms no part of the claimed design.

FIG. 8 shows a top perspective view of a receptacle module for a tabletop media center according to a second embodiment.

FIG. 9 shows a top view of the receptacle module for a tabletop media center according to the second embodiment. FIG. 10 shows a front view of the receptacle module for a tabletop media center according to the second embodiment. FIG. 11 shows a rear view of the receptacle module for a tabletop media center according to the second embodiment. FIG. 12 shows a left side view of the receptacle module for a tabletop media center according to the second embodiment.

FIG. 13 shows a right side view of the receptacle module for a tabletop media center according to the second embodiment.

FIG. 14 shows a top perspective view of the receptacle module for a tabletop media center according to the second embodiment, wherein the tabletop media center shown in broken lines illustrates the environment in which the design is used and forms no part of the claimed design.

(Continued)

FIG. 15 shows a top perspective view of a receptacle module for a tabletop media center according to a third embodiment. FIG. 16 shows a top view of the receptacle module for a tabletop media center according to the third embodiment. FIG. 17 shows a front view of the receptacle module for a tabletop media center according to the third embodiment. FIG. 18 shows a rear view of the receptacle module for a tabletop media center according to the third embodiment. FIG. 19 shows a left side view of the receptacle module for a tabletop media center according to the third embodiment. FIG. 20 shows a right side view of the receptacle module for a tabletop media center according to the third embodiment; and, FIG. 21 shows a top perspective view of the receptacle module for a tabletop media center according to the third embodiment, wherein the tabletop media center shown in broken lines illustrates the environment in which the design is used and forms no part of the claimed design.

The broken lines in the figures depict portions of the receptacle module for a tabletop media center that form no part of the claimed design.
